(57) **CLAIM**

The ornamental design for a positioning label device, as shown and described.

DESCRIPTION

FIG. 1 is a rear perspective view of a positioning label device showing our design.

FIG. 2 is a front perspective view of the positioning label device in FIG. 1.

FIG. 3 is a front elevation view of the positioning label device in FIG. 1.

FIG. 4 is a rear elevation view of the positioning label device in FIG. 1.

FIG. 5 is a left side elevation view of the positioning label device in FIG. 1.

FIG. 6 is a right side elevation view of the positioning label device in FIG. 1.

FIG. 7 is a top plan view of the positioning label device in FIG. 1.

FIG. 8 is a bottom plan view of the positioning label device in FIG. 1; and,

FIG. 9 is a front perspective view of the positioning label device in FIG. 1, in a light-on state.

(Continued)

The broken lines in the drawings are employed to show unclaimed portions of the positioning label device, and form no part of the claimed design.
